(57) **CLAIM**

The ornamental design for a hollow fiber ready to process cart, as shown and described.

DESCRIPTION

FIG. 1 is a perspective view of the hollow fiber ready to process cart showing our new design.

FIG. 2 is a front view of the hollow fiber ready to process cart of FIG. 1.

FIG. 3 is a back view of the hollow fiber ready to process cart of FIG. 1.

FIG. 4 is a left side view of the hollow fiber ready to process cart of FIG. 1.

FIG. 5 is a right side view of the hollow fiber ready to process cart of FIG. 1.

FIG. 6 is a top plan view of the hollow fiber ready to process cart of FIG. 1; and,

FIG. 7 is a bottom plan view of the hollow fiber ready to process cart of FIG. 1.

Portions of the design shown in broken lines form no part of the claimed design.

The design includes a hollow fiber ready to process cart that has three shelves, which is composed of a stainless steel structure. The front end and the back end of the hollow fiber ready to process cart includes a retractable T-Bar configuration to hang bags or filters to strengthen it in order to satisfy the design requirements for the hollow fiber ready to process cart.
